UNITED STATES PATENT OFFICE.

HARRY A. DOUGLAS, OF BRONSON, MICHIGAN.

COWL LAMP.

Original application filed January 27, 1921, Serial No. 440,486. Divided and this application filed April 17, 1922. Serial No. 554,270.

To all whom it may concern:

Be it known that I, HARRY A. DOUGLAS, citizen of the United States, residing at Bronson, in the county of Branch and State of Michigan, have invented a certain new and useful Improvement in Cowl Lamps, of which the following is a full, clear, concise, and exact description.

My invention relates, generally speaking, 10 to circuit continuing devices and also specifically to cowl lamps which are used, for example, upon the dashboards of automobiles. The invention has for its main object the provision of such a construction 15 and assembly of parts that short circuiting paths are avoided, but has other objects or advantages in view as will appear.

In automobile wiring the circuit connectors are such that the manipulator of lamp 20 parts, particularly lamp cowls, are apt to be subject to stray or grounded currents. I avoid this liability by surrounding the incandescent lamp bulb socket or shell by a sleeve which, if metallic, is suitably electrically separated from the lamp holding 25 shell. Where the cowl is employed in conjunction with the lamp, the sleeve is formed with a reduced forward end to support the cowl in suitable relation to the lamp bulb.

30 I will explain the foregoing and other characteristics of my invention more fully by reference to the accompanying drawings showing the preferred embodiment thereof and in which Fig. 1 is a longitudinal sectional view of a cowl lamp constructed in accordance with the preferred embodiment 35 of the invention, this figure being taken generally on line 1—1 of Fig. 2; Fig. 2 is a sectional view on line 2—2 of Fig. 1; Fig. 3

40 is a view on line 3—3 of Fig. 2; Fig. 4 is a view on line 4—4 of Fig. 1; Fig. 5 is a detail view; Fig. 6 is a longitudinal sectional view illustrating a modification; Fig. 7 is a rear end view of the structure shown in 45 Fig. 6; Fig. 8 is a sectional view on line 8—8 of Fig. 6; Fig. 9 is a perspective view of an element that takes part in assembling portions of the structure; Fig. 10 is a view, partially in section and partially in elevation, illustrating a modification; and Fig. 50 50

Fig. 11 is a sectional view on line 11—11 of Fig. 6.

Like parts are indicated by similar characters of reference throughout the different figures.

By reason of the illustrated construction, the mounting sleeve 1 may be metallic. This sleeve is provided with a flange 2 carrying sleeve rivets 3 that assemble the insulating mounting plate 4 with the base of 60 the mounting sleeve. These rivets also serve to permit of the passage of mounting screws through the base flange of the mounting sleeve into some suitable support, such, for example, as the dashboards of 65 automobiles. The metallic shell 5 is surrounded and substantially housed by the mounting sleeve, this metallic shell being suitably assembled with the mounting plate or insulating body 4 that unites the rear 70 ends of the shell and sleeve. The forward end of the shell is formed with bayonet channels 6 which are adapted to receive bayonet projections 7 carried by the base of the incandescent lamp bulb 8, such lamp 75 base constituting the contact carrier. The bulb of the lamp projects forwardly beyond the shell and sleeve and in order that the passage of light therefrom may be limited to a definite path the bulb is partially 80 enclosed by a cowl 9 which is mounted upon the reduced forward end of the shell 1, the base of the cowl engaging the shoulder formed upon the shell where the reduced portion is connected with the balance of 85 the shell.

If the circuit continuing device is a so-called double pole structure, the inner end of the lamp base is provided with two contacts 10 that constitute terminals of the 90 lamp filament and the sleeve encloses two forwardly pressed spring contacts 11 engageable with the contacts 10 to include the lamp in circuit. This double pole structure is illustrated in Figs. 1 to 5, inclusive. In 95 Figs. 6 to 11, inclusive, a single pole structure is illustrated in which case there is but one lamp base contact 10 upon the inner face of the lamp base and but one forwardly spring pressed contact 11 engageable with 100 the contact 10, one terminal of the lamp filament being connected with the metallic sheath that engages the metallic sleeve 5 which is in grounded connection with the source of current that supplies the lamp. In 105 each construction, the shell 5 is desirably fixedly assembled with the insulating body 4 by means of clips 13 having opposite notches 14 that receive ears 15 struck outwardly from the shell whereby the base of 110

the shell is held against the inner face of the plate 4 except where the shell is formed with rearwardly projecting tongues 16 that extend through the plate 4 to prevent the shell 5 from turning and to take part in fixing the angular relation of the shell to the plate. Each clip is formed with an angular ear 17 that engages the rear face of the plate 4 to complete the assembly of the plate and shell.

10 Where the structure is a so-called single pole structure one of the clips is provided with a rearward continuation 18 having threaded holes 19 that receive the binding screws 20 that serve to connect the current conducting 15 wire with the clip provided with the extension whereby the shell connected with the clip may be grounded. In the case of each contact 11, in the two pole structure of Figs. 1 to 5 inclusive, and the single contact 11 of 20 the single pole structure of Figs. 6 to 11, inclusive, there is a flat terminal plate 21 that carries such contact 11 in riveted connection therewith at the front end of the plate, the rear end of the plate being formed 25 with a threaded hole that receives a binding screw 22 for connecting the plate and the contact thereon in circuit. There is a metallic sleeve 23 for guiding each plate 21 which is movable longitudinally of the sleeve 23 enclosing it. The rear end of each sleeve is 30 formed with flanges 24 that define an annular channel between which the mounting plate 4 is gripped. A coiled spring 25 surrounds each sleeve 23, being compressed between the corresponding contact 11 and the forward flange 24. Each contact 11 is thus 35 forwardly spring pressed into engagement with its complemental contact 10 when the contact carrier carrying such complemental contact is fully assembled with the forward 40 end of the shell 5. In the case of a two pole structure, the incandescent lamp is included in circuit by the engagement of both contacts 11 respectively with the contacts 10 45 upon the inner face of the lamp base. In the case of the single pole structure the incandescent lamp is included in circuit when

the single contact 11 fully engages the complemental contact 10 at the center of the lamp base. The coiled spring that urges the 50 contact 11 forwardly, not only engages such contact with its complemental contact 10 in the single pole structure, but also firmly presses the metallic sheath, with which the base of the single pole lamp is provided, 55 laterally against the grounded shell.

Novel characteristics not herein claimed form the subject matter of my original application Serial No. 440,486, filed January 27, 1921, of which the present case is a division 60 and my copending application, Serial No. 678,210 filed Dec. 3, 1923, a division of the present application.

While I have herein shown and particularly described the preferred embodiment of my invention I do not wish to be limited to the precise details of construction shown as changes may readily be made without departing from the spirit of my invention, but having thus described my invention I claim 65 as new and desire to secure by Letters Patent the following:—

In a lamp structure, the combination with a metallic sleeve; of a metallic shell assembled with said sleeve, this shell being 70 formed with a flange; an insulating body uniting the rear ends of said shell and sleeve and constituting a contact carrier, there being rivets passing through said flange and insulating body; a forwardly spring pressed contact upon said insulating body and projecting into said shell; an incandescent lamp whose base is separably coupled with the forward end of said shell and carries a contact that is complemental to the aforesaid 75 spring pressed contact; and a cowl supported upon the forward end of said sleeve, 80 which sleeve end is reduced to form a shoulder for engaging the base of the cowl.

In witness whereof, I hereunto subscribe my name this 27th day of September, A. D. 90 1921.

HARRY A. DOUGLAS.
